[57] ABSTRACT

The display device is comprised to a support base having a recess in the upper portion thereof for receiving the lower end of a vertically disposed display column having a plurality of downwardly angled display shelves on opposite faces. The shelves on one face are staggered with respect to the shelves on the opposite face to define a zig-zag configuration when viewed from the side and each shelf is adapted to hold a plurality of parallelepipeds boxes disposed in side by side relation. The column is constructed of two complementary shells which are secured together in back to back relation.

39. At the upper portion of the lateral walls 36 are two horizontal planar surfaces 40 connecting these walls with inner walls 41 which are symmetrically inclined downwardly toward each other. Each wall 41 has a transverse tooth 42 designed to releasably engage during assembly in corresponding recesses 15a, 17a, in the two lateral walls 15, 17, situated at the base of the column. The inner walls 41 are connected to two inner end walls 43 and to a bottom wall 44 so as to define a recess in the base, in which the lower end of the column is inserted in a form fitting manner. The bottom wall 44 and the inner end walls 43 are provided with grooves 45 adapted to receive the connecting flanges 33 and 34 on the column.

The lower element 46 which constitutes the bottom of the base is comprised of a horizontal wall 47, an inclined lateral edge 48 and a lower planar edge 49 which connects with the lower flange 39. The horizontal wall 47 is centrally provided with a groove 50 in which the groove 45 of the lower wall 44 of the upper element is engaged.

The display device which has been described is of simple construction and inexpensive to produce owing to the fact that complicated equipment for injection molding the device from plastic material is eliminated. It is also very light and has considerable mechanical strength.

The features of the present device can obviously be applied to other devices designed for the same purpose and employing the same innovative concept.

What is claimed is:

1. A display device for parallelepiped-shaped objects comprising a vertically disposed display column having identical zig-zag shaped side walls and a central portion, the opposite faces of which are formed into a plu-

rality of inclined open recesses adapted to receive groups of parallelepipedic objects disposed adjacent to each other, said column comprising two separate complementary vacuum molded plastic shells having peripheral connecting flanges and means for securing said flanges together, and a vacuum molded plastic supporting base having a molded recess in the upper surface thereof in which the lower end of the vertical column engages in a form-fitting manner, the molded recess of the base having two opposed teeth adapted to releasably engage in two recesses provided on the lower end of the column to stabilize the column with respect to the base.

2. A display device according to claim 1, wherein each shell is comprised of two side walls and a plurality of transverse walls which are interconnected in a continuous manner to the side walls and each other to form a series of inclined recesses in which the objects to be displayed are arranged in groups, said recesses having opposed walls provided with longitudinal ribs adapted to hold the individually displayed objects in place, each of said shells being provided at the lower end thereof with a reduced width tapered portion and at the upper end thereof with handle means for lifting and transporting the display device and each of said shells having peripheral flanges for securing said shells together.

3. A display device according to claim 1, wherein the supporting base is comprised of two vacuum molded plastic elements, one of said elements having said recess for securing the lower end of said columns and the other element forming an internal reinforcement for said one element, each of said elements having flanges for connecting said elements together.
